UNITED STATES PATENT OFFICE.

EDDY T. THOMAS, OF NEW YORK, N. Y., ASSIGNOR TO GOLD MEDAL SEWING-MACHINE COMPANY, OF ORANGE, MASS.

SEWING-MACHINE.

SPECIFICATION forming part of Letters Patent No. 240,199, dated April 12, 1881.

Application filed August 13, 1880. (No model.)

To all whom it may concern:

Be it known that I, EDDY T. THOMAS, of New York, New York county, State of New York, have invented an Improvement in Sewing-Machines, of which the following description, in connection with the accompanying drawings, is a specification.

This invention relates to sewing-machines, and is shown embodied in that class of sewing-machines employing an oscillating shuttle and eye-pointed needle, substantially such as described in United States Patent No. 230,677, heretofore granted to me, and to which reference may be had.

15 One feature of this present invention consists in a spiral or twisted shaft, having its surface or outline shaped or curved to correspond with the arc in which the vibrating arm for oscillating the said shaft moves, such construction insuring a close and accurate fit of the fork carried by the said vibrating arm with the said spiral shaft.

Another part of my invention consists in mechanism, hereinafter described, to raise or 25 lower the feeding device and to move it backward and forward positively; also, in a presser-foot bar provided with a collar having a tapering pin adapted to enter a curved and tapering slot in a presser-spring; also, in the combination, with such a presser-bar, pin, and slotted spring, of a holder to hold the presser-bar in adjusted position, with the foot in working position or turned aside; also, in details 30 of construction of the take-up mechanism.

35 Figure 1 represents, in side elevation, a sewing-machine containing my improvements; Fig. 2, an under-side view thereof, a part of the frame being cut away, and the spiral shaft being in section; Fig. 3, a front view of the 40 head of the machine, showing the needle-bar, presser-bar, take-up, and crank and link for moving the needle-bar. Fig. 4 represents the rear end of the machine, with the frame-work broken out. Fig. 5 is a side elevation and 45 front end of the presser-spring for holding down the presser-bar, and section through the conical pin of the presser-bar, the latter being supposed to be lifted; Fig. 6, details of the take-up, its operating-cam and eye-piece, from 50 which the thread is drawn in two or more bights by the take-up lever; Fig. 7, a detail

showing the eccentric pin or hub for the feed-lifting lever. Fig. 8 represents, in detail, the curved spiral shaft on a larger scale, and the blank from which said spiral shaft is made, to 55 more clearly show the inward curve to the said shaft; and Fig. 9 is a detail of the rear end of the lever *i*.

The frame-work *a*, cloth-plate *b*, and head *c* are of usual or suitable construction. The 60 main driven shaft *d* of the machine has at its front end a crank, *d'*, the pin of which is connected with the link *d²*, attached to a pin on a block, *d³*, secured to the needle-bar *d⁴*, provided, as usual, with a needle, *d⁵*.

In sewing-machines heretofore constructed, as far as I am aware, the needle-bar has usually been placed substantially in a line with the shaft *d* and at right angles to its axis; but in this my invention I have placed the needle-bar at one side of the said center, as represented in Fig. 3, so that the said link *d²* and the needle-bar are substantially in the same vertical line when the most strain is exerted upon the needle-bar—viz., just as the needle is 75 penetrating the material being sewed. This construction obviates very materially the wear upon the needle-bar and its bearings, and consequently increases the durability of the machine. At the rear of the crank there is placed 80 upon the shaft *d* a cam, *e*; or, if desired, the hub of the said crank may be turned to constitute the said cam. This cam, as the needle-bar is descending from its highest to its lowest position, is of such shape as to cause the 85 upper end of the take-up lever *e'* to be thrown back into its farthest position away from the eye-piece *e²*; but just as the needle-bar commences to rise the cam, by means of its shape, permits the lower end of the take-up lever to 90 approach the center of the shaft *d*, under the action of a spring, *e³*, the upper end of the take-up lever then moving into the position shown in Fig. 6, where it remains until the needle-bar reaches substantially its highest 95 position, when the cam again operates the take-up lever to throw it back into the position shown in Fig. 3, taking up the slack in the needle-thread and holding it there while the needle again descends. This take-up lever *e'* 100 has two slotted arms, 2 3. (See Fig. 6.) The eye-piece *e²*, which receives the needle-thread,

has three eyes, and the needle-thread, between the spool x and needle, is passed through the said three eyes and through openings of the arms 2 3, as shown in the detail-figure 6. The 5 said take-up lever e' , by reason of its two branches co-operating with the three eyes of the eye-piece, takes up a larger amount of thread with a smaller movement of the lever e' than would be the case had the take-up lever 10 but one arm and it co-operated with two thread-eyes. Substantially such a thread take-up is described in another application for United States Patent filed by me May 12, 1880; but in this present application the eye-piece e^2 15 is made vertically adjustable on the head of the machine by a screw, e^1 . (See Fig. 1.)

The eyes of the take-up lever e^2 being elongated, adjustment of the eye-piece up or down will enable the take-up device e' to take up 20 just the desired quantity of thread. This same shaft d has upon it an eccentric, f , that actuates the connecting-rod f' , forked at its lower end to embrace a ball-like termination, f^2 , of a short link, f^3 , connected by pin 8 with 25 the rear end of the vibrating shuttle-actuating lever f^4 pivoted at f^5 , the said lever, at its forward end, having a fork, f^6 , to embrace the spiral shaft f^7 , provided at its upper end with a shuttle driver or carriage, as represented in 30 my patent before referred to. This spiral shaft f^7 , instead of being of uniform diameter from end to end, as described in the said patent, is shaped, substantially as shown in the drawings, by a suitable cutting or milling tool, so 35 that that part of the spiral shaft along and over which the fork f^6 travels has its edge curved or shaped to coincide with the arc of a circle described from the center, f^5 , about which the shuttle-actuating lever and its fork 40 f^6 turn, the fork f^6 thereby traveling in the same arc. This enables me to drive the spiral shaft more positively and with less friction and wear, and with less lost motion than would occur were the spiral shaft of the same size from 45 end to end.

On the shaft d , at the rear end of the eccentric f , is an eccentric, g , that operates a strap, g' , secured at its lower end to a connecting-rod, g^2 , pivoted at its outer end upon an adjustable fulcrum-block, g^3 , having screwed into 50 it a thumb-nut, g^4 , the shank of which is extended through a slot, g^5 , in the cloth-support b .

The pin g^6 is fitted to slide endwise loosely 55 in the rock-shaft g^7 , and consequently serves as an adjustable arm for the said shaft. The pin g^6 is connected with the fulcrum-block g^3 through the connecting-rod g^2 and the lower end of the strap g' , and the adjustment of block 60 g^3 horizontally serves to move the head of the pin g^6 nearer to or farther from the center of the rock-shaft, thus regulating the throw of said rock-shaft, and consequently the movements of the feed-bar. The farther the fulcrum-block is adjusted toward the left of Fig. 65 4 the shorter the stitch, and vice versa. A headed pin, g^6 , pivoted upon the lower end of

the strap g' , is extended through an opening made for it in the shaft g^7 , so that the movement of the eccentric and strap g' rocks the 70 said shaft g^7 , causing a finger, g^8 , at its front end to act within a notch at the lower side of the feed-bar h and move said feed-bar backward and forward. The toothed feed-bar h is supported at its rear end upon the pin or 75 screw h^2 , and at its front end upon the end 6 of the feed-lever i , it having its fulcrum on an eccentric pin or stud i^2 . (See Figs. 1, 2, and 7.)

The rear end of the lever i has a slot, i^3 , which is entered by the pin 8, that connects the 80 lever f^4 with the short link f^3 , and consequently as the link f^3 is raised and lowered the said pin 8 acts to rock the lever i on its fulcrum i^2 and raise and lower the feed a certain distance 85 at each operation. The eccentric pin or fulcrum i^2 of this lever has connected with it a spring-arm, which co-operates with slots 10 in a segment, m , serving as a locking device to hold the said eccentric fulcrum in adjusted position. Change of position of this eccentric 90 fulcrum enables the operator to cause the feed-bar to be more or less elevated above the throat-plate, in order to adapt the feed to that class of material being moved by it. The presser-bar l has fixed upon it a collar, l' , having a conical projection, 12, that is extended upward in a slot, 13, in the end of the adjustable spring l^3 , of usual construction, controlled as to its extent of downward pressure by the set-screw l^4 , and lifted in the usual manner by a short lever, l^5 . This slot 13 is curved, and is also tapered 95 from its under side upward, in order to fit closely the conical projection 12. This conical projection is provided with a hole tapped to receive a screw, 15, the head of the screw being 100 of greater diameter than the slot 13, so that the spring l^3 , when lifted, will act upon the head of the said screw and lift the presser-bar and its attached foot m' . At times it is desired to 105 turn the presser-foot m' aside from the needle and from above the feed. The curved shape 110 of the slot 13 permits this to be done, and to retain the presser bar and foot in one or other of its two positions.

I have added to the spring l^3 a presser-foot 115 detaining-spring, 16, that operates upon one or the other side of the head of the screw, according to the position of the said screw and the presser-bar l .

I claim—

1. In a sewing-machine, the shuttle-actuating lever f^4 , means to vibrate it, and its fork f^6 , combined with the spiral or twisted shaft f^7 and its shuttle-driver, the said spiral shaft having its edges or parts which are to be acted 125 upon by the fork curved to correspond with the arc of a circle described substantially from the center of motion of the lever f^4 , as and for the purposes set forth.

2. The feed-bar h , rocking-shaft g^7 , provided 130 with finger g^8 , rotating shaft d , eccentric g , and strap g' , combined with the connecting-rod g^2 , its adjustable fulcrum-block, and the pivoted pin extended through an opening in the said

rocker-shaft, the said devices imparting forward and backward movement to the said feeding-bar, substantially as described.

3. The feed-bar *h*, supported at one end on the screw or stud *h*², and at its other end on the feed-dog-lifting lever *i*, the rocking shaft *g*⁷, its finger *g*⁸, and means to rock the said shaft for a greater or less distance, combined with the said lifting-lever *i* and its adjustable eccentric fulcrum pin or stud *i*², and means to adjust and hold it in adjusted position, and to move the lever *i*, substantially as described.

4. In a sewing-machine, a feed-dog and means to reciprocate it, combined with an independent lever to support one end of the said feed-dog, raise and lower it at each stitch, and means to operate the said lever, combined with the adjustable eccentric or stud, which serves as a fulcrum for the said feed-lifting lever, substantially as described.

5. The take-up lever *e'*, having two arms with eyes, a cam to vibrate it, and means to move the cam, combined with the eye-piece having

three eyes, and means to adjust its position to thereby take up or pull back more or less of 25 the needle-thread, all substantially as described.

6. The presser-bar, its collar, having a conical projection, 12, and screw 15, combined with the spring *p*, provided with the curved slot 13, 30 all substantially as described.

7. The spring *p*, provided with the curved slot 13, and the presser-bar, its collar, and conical projection 12, and screw-head 15, combined with the holding-spring 16, adapted to 35 act upon the head 15 at one or the other side, according to its position on the slot 13, to hold the presser-foot bar and the presser in proper axial position, substantially as described.

In testimony whereof I have signed my name 40 to this specification in the presence of two subscribing witnesses.

EDDY TAYLOR THOMAS.
